UNITED STATES PATENT OFFICE.

JOSIAH E. SYMONS, OF BOISE CITY, IDAHO.

WATER ELEVATOR AND MOTOR.

SPECIFICATION forming part of Letters Patent No. 544,755, dated August 20, 1895.

Application filed February 1, 1895. Serial No. 537,015. (No model.)

To all whom it may concern:

Be it known that I, JOSIAH E. SYMONS, a citizen of the United States, residing at Boise City, in the county of Ada, State of Idaho, have invented a certain new and useful Improvement in Water Elevators and Motors, of which the following is a specification.

The object of my invention is to provide an automatic apparatus whereby the force of the current of a stream may be made available for raising water or driving machinery.

It consists of a series of propelling-blades having substantially plane surfaces, which are secured to endless traveling carriers at substantially right angles to the direction of travel thereof and are placed in a stream at an angle to the direction of the current thereof. By securing plane-surfaced blades on the one hand at right angles to the supporting-carriers and, on the other hand, by placing the carriers and blades in the stream at an angle to the direction of the current thereof I secure certain peculiar advantages, which will be hereinafter referred to.

The best embodiment of my invention at present known to me is that shown in the drawings, in which—

Figure 1 is a perspective view of my invention. Fig. 2 is a plan view of a portion thereof. Figs. 3 and 4 are detail views of the propeller-bucket, Fig. 3 being a section on the line 3 of Fig. 4, looking in the direction of the arrow. Fig. 5 is a perspective detail view of a modified construction, showing the use of a guide-rail by the side of the upstream-cable.

a a are endless cables passing over the sheaves *b b*, *c c*, and *d d*. Of these sheaves *b b* are suitably journaled on the upstream-support *A*, and *c c* and *d d* are journaled in upstream standards *B*, rising from the downstream-support *C*. These supports *A* and *C* are preferably boats suitably anchored and maintained the proper distance apart by the planks *D D*. The supports may, however, consist of piles or other rigid standards. They are so placed that the apparatus will stand at an angle, preferably about thirty degrees, to the direction of the current. Pivotaly secured to the cables *a a*, at right angles thereto, by means of the clamps *e e*, the rod *f*, and the straps *g g*, are the propellers *h*. If the apparatus is to be used for raising water, as is the

form illustrated in the drawings, buckets *i* are formed on the downstream or forward side of the propellers. These buckets are 55 constructed in the manner shown in the drawings. Their ends are made at an angle to the propeller-blade, so that they may not form an obstruction to the passage of the current, and their bottoms are formed at an angle, so that the current may tend to lift them and relieve the cables of a portion of the weight. Diagonal chains *j j* hold the propeller in a vertical working position. The force of the current bearing against the propellers *h* 60 held thus vertically causes the propellers and cables to travel toward the downstream-support, lifting the filled buckets up the standards *B* and discharging their contents into the trough *E*, from whence it flows by gravity 70 to the desired points. In order that one cable may not work ahead of the other and twist the propellers, I provide the diagonal guy-chains *k* and allow each of the sheaves *b b*, *c c*, and *d d* to turn independently of its neighbor by 75 journaling one or both loosely upon the shaft.

Projecting from each end of the propeller-blade, near the bottom thereof, is the cranked axle *l*, upon which is secured the antifriction-roller *m*. This construction serves a double 80 purpose. It will be seen that when the bucket full of water is passing from its vertical to its downwardly-inclined position as the cables go over the sheaves *d d* the bucket hangs between the sheaves and forms the chord of the 85 sheave-arc, while the cables are traveling in the arc. Thus the lower end of the bucket is traveling slower than the cables against which it bears, and hence must slide back upon them. The antifriction-rollers *m* allow 90 the buckets to do this without excessive wear upon the cables, which would be the case without rollers. The cranking of the axle *l* causes the bucket to be tipped suddenly and its contents to be discharged with less loss 95 than otherwise. During the descent of the buckets the cranked axles hold them above the cables, and when passing around the sheaves *b b* they drop over and are properly filled. The chains *j j*, which hold the propellers when working in a vertical position, unite where they cross into the ring *n*. By hooking these rings onto the hooks *o* on the rods *f* the buckets may be maintained in a 100

folded-up position, and thus the speed of the apparatus is gradually checked. After the buckets are folded up the upper boat A may be drawn in to the bank and the apparatus 5 will remain at rest.

The angular position of the apparatus secures independent pressure upon each of the propeller-blades, as one blade does not shield another. Since the propeller-blades have 10 plane surfaces on their current sides and are placed at right angles to the carrying-cables and at an angle to the direction of the current and are free to move in the direction of the cables, it follows that the force of the current 15 upon the propellers will be all expended in driving them in the direction of their travel, and there will be no tendency for the cables to sag downstream. This operation will only result when the propeller-blades 20 have substantially plane surfaces and are at substantially right angles to the direction of cable travel. This is important, as it obviates the necessity for guide-rails or other appliances to prevent lateral sagging of the cables. 25 In very turbulent streams, however, and in streams where a rocky bed causes the current to form eddies, it is sometimes desirable to provide a guide to prevent swaying of the cables. Such a construction is shown in Fig. 5, 30 where the upstream-clamp e is extended into or connected with the arm p, to which is adjustably secured the grooved roller q. This roller rides upon the T-rail or inverted deck-beam r, which is supported, preferably, in a 35 somewhat tipped position across the stream parallel to the lower cables.

Although I have shown the apparatus equipped only for elevating water, it is obvious that it is adapted for other purposes, such 40 as driving mills, &c.

Various changes of form, proportion, and construction may, of course, be made without departing from the spirit of my invention, and I do not wish to be understood as limiting 45 myself to any specific construction further than is pointed out definitely in the claims.

Having thus described my invention, what I claim as new, and desire to secure by Letters Patent, is—

50 1. In a water motor, in combination, an endless flexible traveling carrier, supported partly in a stream and partly above the stream and at an angle less than a right angle to the direction of the current thereof and having each point thereof adapted to move throughout in one substantially vertical plane, a series of blades having substantially plane surfaces and connected to said carrier at substantially right angles to the direction of travel thereof, whereby the blades are adapted to move down stream in the water and upstream out of the water, for the purpose specified.

55 2. In a water motor, in combination, an endless flexible traveling carrier supported partly in a stream and partly above the stream and at an angle less than a right angle to the

direction of the current thereof and having each point thereof adapted to move throughout in one substantially vertical plane, a series of blades having substantially plane surfaces and pivotally connected to said carrier at substantially right angles to the direction of travel thereof and adapted to depend therefrom in the water when they are traveling down-stream, all operating substantially in the manner described, whereby the blades are adapted, after having moved down-stream in the water, to move up-stream out of the water and whereby free egress is allowed for the water after it has acted upon any blade, for the purpose specified.

3. In a water elevator, the combination with two supports located obliquely opposite, one on each side of a suitable portion of the width of a stream of water, of carrier-wheels carried by said supports and adapted to revolve in substantially vertical planes, an endless flexible traveling carrier mounted upon said wheels and adapted to move up-stream-ward out of the water, propeller-blades pivotally connected to said carrier at substantially right angles to the direction of travel thereof, and buckets attached to the propeller blades, for the purpose specified.

4. In a water elevator, in combination, supports located obliquely with reference to the current of a stream between them, carrier-wheels mounted in said supports, an endless flexible carrier adapted to travel around said wheels in substantially first a horizontal plane, then a vertical plane and then a diagonal plane back to the starting point, propeller-blades pivotally connected to said carrier at substantially right angles across the same, said propeller-blades depending vertically in the water while said carrier is traveling in said horizontal plane whereby free egress is allowed the water after it has acted upon any blade, said propeller-blades assuming positions approximately parallel to said carrier while traveling in the said vertical and diagonal planes, and buckets secured to said blades, for the purpose specified.

5. In a water elevator, in combination, a pair of carrier-wheels on a substantially horizontal axis suitably mounted in a support, two pairs of carrier-wheels on substantially horizontal axes one higher than the other mounted in a second support, said supports being placed obliquely with reference to the direction of the current of a stream between them, two endless cables parallel to each other and each traveling around three of said wheels, propeller-blades pivotally connected to said cables at substantially right angles thereto, buckets secured to said propeller-blades, means for maintaining said propeller-blades perpendicular to the plane of the cables during a portion of their travel, for the purpose specified.

6. In a water motor, in combination, carrier-wheels, an endless carrier mounted upon said wheels and having parallel members, cross-

rods connecting said members, propeller-blades supported by said cross-rods, means for limiting the movements of the propeller-blades, and flexible braces arranged diagonally between the members of the carrier, substantially as specified.

7. In a water motor, the combination with carrier-wheels, and an endless carrier mounted upon said wheels, of propeller-blades connected to the carrier and adapted to be folded parallel with or extended perpendicular to the plane of the same, limiting or guy chains connected to the free edges of the propeller-blades and attached at the other end to the carrier, said chains being arranged in pairs with their members intersecting, rings arranged at the intersection of said chains, and hooks for engaging the said rings to secure the blades in their folded positions, substantially as specified.

8. In a water elevator, the combination with carrier-wheels, and an endless carrier mounted thereon, of propeller-blades swiveled in the

carrier, means for holding said blades in their operative positions, and buckets carried by said blades and having downwardly and forwardly inclined bottoms, substantially as specified.

9. In a water elevator, the combination with carrier-wheels, and an endless carrier mounted thereon, of propeller-blades pivotally connected to said carrier, means for holding said blades in their operative positions, and buckets formed upon the down-stream side of said blades, said buckets having their down-stream sides narrower than said propeller-blades whereby the up-stream edges of said buckets present no obstruction to the current when the carrier travels at an appropriate angle to the direction of the current, substantially as specified.

JOSIAH E. SYMONS.
